Pennie Davis Morris Edwards
ATTORNEYS

UNITED STATES PATENT OFFICE.

THOMAS J. MADIGAN, OF NEW YORK, N. Y.

SADIRON.

Application filed January 3, 1922. Serial No. 526,593.

To all whom it may concern.:

Be it known that I, THOMAS J. MADIGAN, a citizen of the United States, residing at New York, in the county of New York, State 5 of New York, have invented certain new and useful Improvements in Sadirons; and I do hereby declare the following to be a full, clear, and exact description of the invention, such as will enable others skilled 10 in the art to which it appertains to make and use the same.

My invention is an improvement in sad irons, and relates particularly to mechanism for holding normally open circuit controlling switches for electrically heated sad irons closed during the preliminary heating of the iron. In my prior application, Serial 15 No. 516,302, filed November 19, 1921, I show and describe an improvement in electrically heated sad irons, wherein a normally open circuit controlling switch is disposed below the grip of the handle, in position to be closed, and to be held closed, by the grasp 20 of the user on the grip. Before commencing the ironing operation, the current must flow for a time, to heat the iron to the proper temperature, and with the type of iron forming the subject matter of the above application, it is necessary to hold the switch closed manually during this preliminary heating.

Any mechanism in connection with the iron or handle, for holding the switch closed is objectionable. The user is liable to forget to release such mechanism when the iron 35 is set aside, with consequent overheating, and liability to damage. Even when an iron provided with such mechanism, that is with means in connection with the iron or handle for holding the switch closed, is set 40 upon a heat insulated stand during the heating of the iron, there is liability to damage, should for instance, the iron be accidentally displaced from the stand.

In the present invention, I provide means 45 in connection with a usual type of heat insulated stand for the iron, and wholly independent of the iron and handle, to hold the switch closed while the iron is on the stand, and so arranged that when the iron is displaced from the stand, the switch is at once 50 released from the holding means. I also provide a standard so constructed that it may be connected to the usual type of insulated stands consisting of spaced plates 55 without the use of screws, rivets, bolts or

clamps, merely by pushing a portion of the standard between the plates.

In the drawings:

Figure 1 is a side view of the stand with the iron in place, and with the handle partly 60 broken away to show the switch.

Figure 2 is a section on the line 2—2 of Figure 1.

Figure 3 is a side view of the handle, partly broken away, to show the switch, and with 65 the switch in open position.

In the present embodiment of the invention, the iron comprises a body 1 of usual construction, having connected therewith a handle 2, spaced apart from the body by 70 plates 3. One of these plates 3 carries the usual plug socket 4, in which is received the plug 5, and one of the lead wires in the flexible connection 6 is looped into the handle as indicated at 7. A switch is arranged 75 within the handle, the switch being interposed in the loop 7, and a switch arm 8 is provided for closing the switch, the switch being normally open. The switch arm 8 is disposed beneath the grip or handle 2 in 80 such position that it may be engaged by the fingers of the user when the handle is grasped, to move the arm into closed position. The ends of the loop 7 are connected to contact plates 9, one of which is shown, the said plates being insulated from each 85 other and supported by a suitable base 10, within a recess 11 in the grip.

The switch comprises members 12 and 13, 90 pivotally connected, one of the members 12 being pivoted to the base as indicated at 17, while the other member 13 carries contact buttons 14 for engaging the contact plates 9, to electrically connect said plates. Springs 15 and 16 are so connected with the members 12, and with the base, that the members cannot hold the position of Figure 1, when the arm 8 is released, but immediately return to the position of Figure 3. The arm 8 has an angular portion 18, which hooks over a pivot pin 19 on the base, and the angular portion engages a pin 20 on the member 15, to swing said members into the position of Figure 1, the springs 15 and 16 returning the parts to the position of Figure 3, when the switch arm 100 is released. The arrangement is such that the switch arm must be held against the grip, in order to hold the circuit closed, and whenever the iron is set aside the switch 105 opens the heating circuit.

With the above construction of iron, it is necessary to hold the switch closed, for a time, before using, in order that the iron may attain the proper temperature for ironing. The use of any means in connection with the handle or with the iron for holding the switch closed would be objectionable, because the user might forget to release said means, thus retaining the circuit closed when the iron is set aside. When the iron is on the heat insulated stand, however, over-heating is of importance only in so far as it may damage the iron. Hence I provide mechanism in connection with the stand, for holding the switch arm in closed position, when the iron is on the stand, but wholly independent of the handle and of the iron, so that the switch arm is immediately released when the iron is displaced from the stand. The said mechanism comprises a standard 21, having means at one end for engaging the stand, and having at the other a lateral arm 22 extending into position to engage the switch arm 8 and move the same to close the switch when the iron is on the stand. The standard in the present instance, is constructed of wire, bent to shape. Referring to Figure 2, it will be seen that that portion of the standard which engages the stand is bent into inverted V shape, as indicated at 23, the V being of sufficient depth such that the apex thereof will engage one of the plates 24 of the stand, while the arms of the V will engage the other plate 25 of the stand. The extremity of this portion of the standard has a laterally bent lug 26, which prevents tilting of the stand sidewise. The lateral arm 22 is formed by doubling the wire upon itself. The standard is only intended to be used during the preliminary heating of the iron, or when the iron is set aside for a few moments, to prevent cooling of the same. When the iron is placed on the stand after the ironing is finished, the switch arm is permitted to take the position of Figure 3, that is it is permitted to move into open position. When in this position, the switch arm will be below the lateral arm of the standard, and the circuit will be open.

It will be obvious that the standard might be constructed in many different ways, the essential features thereof being the lateral arm and the means for engaging the stand for holding the standard erect.

In order to protect the insulation of the looped lead wire 7, I arrange upon said wire beads indicated at 27, the said beads being of any suitable material.

I claim:

1. In combination with an electrically heated iron having a normally open circuit controlling switch provided with an operating arm disposed below the handle in position to be closed by the fingers of the user when the handle is grasped, a heat insulated stand for the iron having means for engaging the switch when the iron is on the stand to close the switch and released from the switch when the iron is disposed from the stand, said means comprising a standard frictionally engaged with the stand and having a lateral arm extending beneath the handle when the iron is on the stand 65 70

2. In combination with an electrically heated iron having a normally open circuit controlling switch provided with an operating arm beneath the handle in position to be grasped and closed by the fingers of the user when grasping the handle, a heat insulated stand comprising connected plates spaced apart from each other, and a standard having means extending between the plates and engaging said plates to hold the standard upright, the standard having a lateral arm extending beneath the handle of 80 85 the iron when the iron is on the stand.

3. In combination with an electrically heated iron having a normally open circuit controlling switch provided with an operating arm disposed below the handle, a stand comprising spaced connected plates, and a standard having means engaging between the plates to support the standard in erect position, and having means for engaging the switch to close the same when the iron is 90 95 placed upon the stand.

In testimony whereof I affix my signature.
THOMAS J. MADIGAN.
